CHOKE VALVE OPERATING MECHANISM

Lester E. Perrine, Detroit, Mich., assignor to General Motors Corporation, Detroit, Mich., a corporation of Delaware

Application March 11, 1935, Serial No. 10,512
Renewed February 1, 1940

19 Claims. (Cl. 123—119)

This invention relates to mechanisms for facilitating starting and insuring proper and continuous operation of an internal combustion engine when its temperature is below that at which it is 5 designed to operate.

The invention resides in mechanisms for automatically maintaining the choke valve of the carburetor of an internal combustion engine so adjusted as to insure that the combustible mixture supplied to the engine by the carburetor, while the engine is being started and when its temperature is below that at which it is designed to operate, will contain the optimum proportions of fuel and air. The mechanisms are improvements over that disclosed in my copending application, Serial No. 602,267, filed March 31, 1932, principally, in that there is incorporated therein, to insure more accurate adjustment of the choke valve, means whereby the position of the choke valve is affected by the pressure within the induction system of the engine on the engine side of the carburetor, as well as by the temperature of the engine or some part thereof.

To insure, after the engine has been started, 25 that it will at all times receive sufficient combustible mixture to insure proper and continuous operation thereof without making it necessary at any time to supply to the engine while it is idling more combustible mixture than is necessary to insure proper and continuous operation thereof, there is preferably employed in conjunction with the mechanism referred to in the next preceding paragraph, mechanism whereby the extent to 30 which the throttle valve of the carburetor of the engine may be closed is rendered dependent upon the temperature of the engine or some part thereof. The latter mechanism is, however, claimed, not in this application, but in my copending application, Serial No. 618,225, filed June 20, 1932, 35 of which this application is, in part, a continuation.

For a better understanding of the nature and the objects of the present invention, reference is 40 made to the following specification in which there are described the preferred embodiments of my invention which are illustrated in the accompanying drawings:

In the accompanying drawings:

50 Figure 1 is a view in which there is shown, mainly in elevation, mechanism in which my invention is embodied installed on an internal combustion engine.

55 Figure 2 is a top plan view of the mechanism shown in Figure 1 with the cover removed.

Figure 3 is a section taken on the line 3—3 of Figure 2.

Figure 4 is a section taken on the line 4—4 of Figure 2.

Figure 5 is a perspective view of an element of the mechanism shown in Figures 1 and 2 for limiting the closing movement of the throttle valve of the carburetor shown in Figure 1.

Figure 6 is a fragmentary view, corresponding to Figure 3, of a modified form of the mechanism shown in the preceding figures.

Figure 7 is a view, corresponding to Figures 3 and 6, of another modified form of the mechanism shown in Figures 1 to 5.

Figure 8 is a view, corresponding to Figures 3, 6 and 7, of still another modified form of the mechanism shown in Figures 1 to 5.

Figure 9 is a view, in which there is shown, partly in elevation and partly in section, another embodiment of the invention illustrated in the preceding figures.

In Figure 1 of the drawings, there is shown part of the induction system of an internal combustion engine which includes a carburetor 10, into which air is drawn through the conduit 11 and from which combustible mixture is discharged through the conduit 12, and a manifold 13 through which the combustible mixture discharged from the conduit 12 is conducted to the intake ports of the cylinders of the engine. Within the conduit 12 on the shaft 14, there is mounted a throttle valve 15 of the butterfly type and within the conduit 11 on the shaft 16, there is mounted a choke valve 17 of the butterfly type which is notable only in this, that, as shown in the drawing, the portion thereof which moves inwardly as the valve opens is of greater area than the portion on the opposite side of the shaft 16 and, consequently, that flow of air into the carburetor will tend to open it.

The embodiment of my invention which is shown in Figures 1 to 5 and the modified forms thereof which are shown in Figures 7 and 8 include a generally receptacular body 18 which is seated on and secured by means of screws 19 to the intake manifold 13. The open side of the body 18, which is preferably made of brass or some other non-magnetic material, is closed by a cover 20 which is preferably made of the same material.

In the opposite side walls of the body 18, adjacent one end, there are formed bearings 21 in which there is journaled a shaft 22 which extends through the body. On one end of the shaft 22, without the body, there is fixed an arm 23 which is

connected by a link 24 to an arm 25 which is fixed on the shaft 16 on which the choke valve 17 is mounted. The opposite end of the shaft 22 extends into a cup-shaped housing 27 which is 5 adjustably secured by a clamp 28 to an extension of the adjacent bearing 21. Within the cup-shaped housing 27, there is located a thermo-sensitive bimetallic coil spring 26 whose outer end is secured to the housing and whose inner end is 10 secured to the end of the shaft 22 which is located within the housing.

Within the body 18, between the shaft 22 and the end of the body farthest from the shaft, there is located a U-shaped permanent magnet 33 15 which is adjustably clamped by a screw 35 and a plate 36 to a boss 37 which is formed on the inside of the body. To the shaft 22, within the body 18, there is adjustably clamped the intermediate portion of an L-shaped keeper 29 which 20 is preferably made of a ferrous metal and spaced from the side walls of the body by sleeves 30. When the choke valve 17 is in the position in which it is shown in the drawings, i. e., in its fully closed position, the keeper 29 occupies the 25 position in which it is shown in the drawings, that is to say, its shorter arm 31 extends approximately vertically downwardly and its longer arm 32 extends approximately horizontally and overlies the poles of the magnet 33.

On the outer side of the end wall of the body 18 farthest from the shaft 22, there is formed a hollow boss 38 into which there extends the closed end of an expansible and contractible metal bellows 39. On the open outer end of the bellows 39, there is formed a flange 40 which is seated on the outer end of the boss 38. The outer end of the bellows is closed by and the bellows is secured to the boss through a plate 41 which is seated on the flange 40 and secured 30 to the boss 38. The interior of the bellows is connected to the interior of the intake manifold 13 by communicating bores 42, 43 and 44 in the plate 41, the body 18 and the upper wall of the intake manifold. To the closed inner end of 35 the bellows 39, there is connected a short rod 45 which extends into the interior of the body 18 through an opening 46 in the end wall thereof. The end of the rod 45 which is located within the interior of the body 18 is pivotally connected 40 to an L-shaped lever 47 at the junction of its arms 48 and 50. Through the shorter arm 48 of the lever 47 which extends upwardly from its junction with the longer arm 50 extends a pin 49 which is carried by the body 18 and serves as 45 a fulcrum for the lever. The longer arm 50 of the lever 47 extends approximately horizontally from its junction with the shorter arm 48 to a point near the distant end wall of the body 18 and at its extremity is pivotally connected by a 50 pin 51 to the lower end of a link 52. The upper end of the link 52 is pivotally connected by a pin 53 to the keeper 29 above the shaft 22 and on the side thereof farthest from the fulcrum of the lever 47.

In the drawings, the hereinbefore described mechanism is shown mounted on the intake manifold 13 because, when it is so installed on the engine to which the drawings relate, the thermo-sensitive element 26 is, as shown in Figures 2 and 4, located in such close juxtaposition to the exhaust manifold 54 of the engine that it is affected by the heat radiated therefrom. It will, of course, be understood that, in engines in which the arrangement of the intake and exhaust manifolds differs from that illustrated in the draw-

ings, it may be found desirable, in order so to locate the thermo-sensitive elements that they will be affected by the heat radiated from the exhaust manifolds, to mount the mechanisms on parts of the engines other than the intake manifolds, and, moreover, if it be so desired, the mechanisms may be so mounted that the thermo-sensitive elements will be affected by the heat radiated from parts of the engines other than the exhaust manifolds.

The thermo-sensitive element 26 is so constructed and arranged that, as its temperature rises, it tends to rotate the shaft 22 in a counter-clockwise direction when it is viewed as shown in Figures 1 and 3 and to open the choke valve 17, that, as its temperature falls, it tends to rotate the shaft 22 in a clockwise direction and to close the choke valve and that, when its temperature falls below a predetermined value (e. g., 70° F. to 80° F.), if unresisted, it will maintain the choke valve in its fully closed position. From what is said in the next preceding sentence, it will be apparent that the thermo-sensitive element 26, when its temperature is below a predetermined value, tends to maintain the choke valve in its fully closed position and, when its temperature equals or exceeds this value, tends to regulate the position of the choke valve in accordance with its temperature and, since the thermo-sensitive element is affected by the temperature of the exhaust manifold 54, in accordance with the temperature of the exhaust manifold. Moreover, it will be noted that the attraction of the magnet 33 for the arm 32 of the keeper 29 tends to prevent rotation of the shaft 22 in a counter-clockwise direction and, therefore, to maintain the choke valve in its closed position.

When an engine on which the mechanism shown in Figures 1 to 5 and hereinbefore described is installed is not operating, the positions 40 of the parts of the mechanism will depend upon the temperature of the exhaust manifold of the engine. If the engine is sufficiently heated, the thermo-sensitive element 26 will maintain the choke valve 17 partially or fully open and the 45 arm 32 of the keeper 29 out of the effective field of attraction of the magnet 33. Under these conditions, the position of the choke valve will, while the engine is being started, be controlled entirely by the thermo-sensitive element 26, the volume 50 of air which is flowing through the conduit 11 and the suction within the intake manifold 13 which tends to contract the bellows 39 and, through it, the rod 45, the lever 47, the link 52, the shaft 22, the arm 23, the link 24 and the 55 arm 25, to open the choke valve.

If, however, when the engine is not operating, it becomes sufficiently cold, the thermo-sensitive element 26 will move the choke valve sufficiently toward its closed position to bring the arm 32 of the keeper 29 into the effective field of attraction of the magnet 33 which will tend to move the keeper further in a clockwise direction and, consequently, to close the choke valve completely. Since the force exerted by a permanent magnet on an object varies inversely as the square of the distance separating the magnet and the object, the strength of the closing force exerted by the magnet 33 will depend upon the distance which separates the magnet 33 and the arm 32 of the keeper 29. Under the conditions described in the preceding portion of this paragraph, it is obvious that, while the engine is not operating, the position of the choke valve 17 will depend partly upon the temperature 70 of the thermo-sensitive element 26 and partly 75

upon the attractive force exerted by the magnet on the arm 32 of the keeper 29. If under these conditions the engine is cranked, the tendency of the air flowing through the conduit 11, plus the tendency of the suction within the intake manifold to open the choke valve will be resisted by the attractive force of the magnet 33 for the arm 32 of the keeper 29 and the tendency of the thermo-sensitive element 26 to maintain the choke valve 15 in its closed position. Consequently, since under the conditions in which the arm 32 of the keeper 29 is located within the effective field of attraction of the magnet, the latter dominates the thermo-sensitive element 26 in determining the position of the choke valve, the position of the choke valve will under the conditions under consideration be determined by the magnet until such time as the flow of air through the conduit 11, plus the suction within the intake manifold 13 becomes sufficient to overcome the attractive force of the magnet for the arm 32 of the keeper 29, plus the tendency, if any, of the thermo-sensitive element 26 to maintain the arm 32 of the keeper 29 in the effective field of attraction of the magnet. When the flow of air through the conduit 11, plus the suction within the intake manifold 13 becomes sufficient to overcome the attractive force of the magnet for the arm 32 of the keeper 29, plus the tendency, if any, of the thermo-sensitive element 26 to maintain the arm 32 of the keeper 29 within the effective field of attraction of the magnet, the arm 32 will be moved out of the effective field of attraction of the magnet and, thereafter, until conditions again become such as to bring the arm 32 of keeper 29 back into the effective field of attraction of the magnet, the position of the choke valve will depend entirely upon the temperature of the thermo-sensitive element 26, the flow of air through the conduit 11 and the suction within the intake manifold 13.

Since the ratio of fuel to air in the combustible mixture which an internal combustion engine requires for most satisfactory operation is, in part, a function of the pressure in the induction system of the engine on the engine side of the carburetor, the choke valve adjusting mechanism shown in Figures 1 to 5 is capable of maintaining the ratio of fuel to air in the combustible mixture supplied to the engine more nearly at its optimum value under the several conditions of operation of the engine than is the mechanism disclosed in my previously mentioned application, Serial No. 602,267, since when the mechanism shown in Figures 1 to 5 is employed, both the interval during which the position of the choke valve is determined by the magnet and the position of the choke valve after the arm 32 of the keeper 29 has been moved out of the effective field of attraction of the magnet are affected by the pressure within the intake manifold as well as by the temperature of the engine and the flow of air through the conduit 11.

To insure that the choke valve will be at least partially open when the throttle valve is opened to a predetermined extent, there is preferably provided in conjunction with the mechanism hereinbefore described means whereby the arm 32 of the keeper 29 will be moved out of the effective field of attraction of the magnet 33 when the throttle valve has been opened to a predetermined extent. To this end, I have provided, as shown in the drawings, bearings 56 in the opposite side walls of the body 18 directly below the bearings 21. In these bearings, there is journaled a shaft 55 on which, within the body 18, there is formed a cam

surface 57 which is adapted to be brought into engagement with the arm 31 of the keeper 29 to open the choke valve to a predetermined extent when the shaft has been rotated through a predetermined angle. To interconnect the shaft 55 with the throttle valve 15 so that the angular position of the shaft will be determined by the position of the throttle valve, there is fixed to one end of the shaft 55 an arm 58 which is interconnected through a link 59, a bell crank 60 and a link 61 to an arm 62 which is fixed to the shaft 14 on which the throttle valve 15 is mounted. It will be apparent from a consideration of the structure described in the preceding portion of this paragraph that when the throttle valve 15 is opened to a predetermined extent, the cam surface 57 on the shaft 55 will engage the arm 31 of the keeper 29, rotate it in a counter-clockwise direction and positively partially open the choke valve.

To insure, after the engine has been started, that the throttle valve 15 will not be closed to such an extent as to prevent under any conditions sufficient combustible mixture to insure proper and continuous operation of the engine being supplied to the cylinders of the engine, without making it necessary at any time to supply to the engine while it is idling more combustible mixture than is necessary to insure proper and continuous operation thereof, there is provided in conjunction with the hereinbefore described mechanism, mechanism whereby the extent to which the throttle valve may be closed is rendered dependent upon the temperature of the engine or some part thereof. This mechanism includes a two-armed lever 62 which is fulcrumed intermediate its ends on the shaft 55. On one of the arms 63 of the lever 62, there is formed an ear 64 which overlies a portion of the arm 58 which is fixed on the shaft 55. The other arm 65 of the lever 62 terminates above a pin 66 which is fixed to the side of the body 18 on which the thermo-sensitive element 26 is located. On the pin 66, there is rotatably mounted a sleeve 67 on whose cylindoidal wall, directly below the end of an adjusting screw 68 carried by the arm 65 of the lever 62, there is formed a cam-like projection 69. On the outer end of the sleeve 67, there is formed a housing 70 in which there is located a bimetallic thermo-sensitive coil spring 71 whose outer and inner ends are fixed, respectively, to the housing 70 and to the outer end of the pin 66.

A spring 72 whose opposite ends are connected, respectively, to the arm 65 of the lever 62 and to the body 18 tends to rotate the lever 62 in a counter-clockwise direction, when it is viewed as shown in Figure 1, and to maintain the ear 64 in contact with the upper surface of the arm 58. When the engine is operating at any speed greater than idle, the spring 72 maintains the screw 68 out of contact with the cam 69 and prevents it interfering with rotation of the element 67-70 on the pin 66.

It will be noted that when the mechanism under consideration is installed on an engine as shown in the drawings, the thermo-sensitive element 71 is so located that it is affected by the heat radiated from the exhaust manifold 54 and is so constructed and arranged that as its temperature rises it tends to rotate the element 67-70 to a position in which the screw 68 is adapted to contact with the portion of the cam 69 nearest the axis of the sleeve 67 and that as its temperature falls it tends to rotate the element 67-70 to a position in which the screw 68 is adapted to contact with the portion of the cam 69 most distant from the axis of the sleeve 67. When the throttle valve 15 is moved toward its closed position, the

arm 58 is moved into engagement with the ear 64 on the lever 63 and causes the lever 63 to rotate in a clockwise direction, when it is viewed as shown in Figure 1, until the screw 68 engages the cam 69 which functions to limit the movement of the throttle valve toward its closed position. From what has been said in the preceding portion of this paragraph, it will be apparent that the cam 69 will stop the closing movement of the throttle valve 15 when the throttle valve is further from its fully closed position when the engine is cold, than when it is hot. The cam will, of course, be so formed and the thermo-sensitive element 71 so calibrated that under no condition can the throttle valve be closed to such an extent as to prevent sufficient combustible mixture to insure proper and continuous operation of the engine being supplied to the cylinders thereof and that under no condition, when the screw 68 is in contact with the cam, will 20 any more combustible mixture than is necessary to insure proper and continuous operation of the engine be supplied to the cylinders thereof.

While, since in the form shown herein the thermo-sensitive element 71 is not sufficiently powerful to rotate the element 67-10 on the pin 66 when the screw 68 is in contact with the cam 69, the thermo-sensitive element will not function to open the throttle valve and, consequently, to facilitate starting of the engine, it will be necessary to open the throttle valve slightly by other means such as the hand throttle control, the accelerator pedal or an interconnection between the throttle valve and the self-starter; it is, of course, possible to make the thermo-sensitive element 71 sufficiently powerful that it will open the throttle valve to the extent necessary to facilitate starting.

The mechanism shown in Figure 6 differs from that shown in Figures 1 to 5 only in the means through which the force exerted by the suction 40 within the intake manifold is transmitted to the link 52. In the mechanism shown in Figure 6, this means includes a hollow boss 73 whose location is similar to that of the boss 38 and a cover 74 between which are clamped the outer edges of a 45 flexible diaphragm 75 whose central portion is clamped between two plates 76 and 77. A screw 78 which extends through the cover 74 engages the outer plate 77 at a point above the center of the diaphragm 75. From the inner plate 76, 50 there projects an arm 79 which extends into the interior of the body 18 through a vertical guide slot 80. The extremity of the arm 79 which is located within the body 18 is connected to the link 52 by a pivot 81. The space enclosed by the cover 55 74 and the diaphragm 75 is connected to the interior of the intake manifold 13 by communicating bores 82, 83 and 44 in the cover 74, the body 18 and the upper wall of the intake manifold 13. It will be apparent from a consideration of the 60 structure described in the preceding portion of this paragraph that the suction within the intake manifold 13 will tend to flex the diaphragm 75 to the right when it is viewed as shown in Figure 6, and, consequently, to rock the element 77-76-79 65 about its fulcrum 78 from the position in which it is shown in solid lines to that in which it is shown in dot-and-dash lines and to move the choke valve to its open position.

The mechanism shown in Figure 7 differs from 70 that shown in Figures 1 to 5 only in that there is included in the former the thermo-sensitive element designated by the reference character 84. This thermo-sensitive element includes a bimetallic thermo-sensitive strip 85 of which one end is seated on and secured by a screw 86 to a boss 87

formed on the upper surface of the arm 32 of the keeper 29. The opposite end of the strip 85 carries a pin 88 which projects into an opening 89 which extends vertically through the arm 32 directly above one of the poles of the magnet 33. 5 The strip 85 is, of course, affected by the heat radiated from the engine on which the mechanism is installed and is so constructed and arranged that it tends to move the pin 88 downwardly when its temperature rises and upwardly when its temperature falls. When the temperature of the engine on which the mechanism is installed is below a predetermined value, the strip 85, of course, maintains the lower end of the pin 88 at or above the level of the lower surface of the arm 32 of the keeper 29 and, consequently, the thermo-sensitive element 84 does not affect the operation of the mechanism. However, when the temperature of the engine rises to a value which exceeds the mentioned predetermined value, the pin 88 moves through the opening 89 to a position in which it can engage the pole of the magnet 33 with which it is associated and, consequently, prevents the arm 32 of the keeper 29 from moving within or remaining within a predetermined distance of the magnet 33. This distance varies inversely with the extent by which the temperature of the engine exceeds the mentioned predetermined value until the strip 85 engages the upper surface of the arm 32 of the keeper 29 since the distance which the pin 88 projects below the lower surface of the arm 32 varies in this manner. The pin 88 is preferably made of such length that, when the strip 85 engages the upper surface of the arm 32, it prevents the arm 32 from moving within or remaining within the effective field of attraction of the magnet 33. 30 35

The effect of the presence in the mechanism of the thermo-sensitive element 84 is to vary, inversely with the temperature of the engine, from 40 a value which approaches its maximum to a value which approaches zero, the closing force exerted by the magnet 33 on the choke valve 17 when the temperature of the engine exceeds a predetermined value. The presence in the mechanism of 45 the thermo-sensitive element 84 is decidedly efficacious in that, by reducing the interval during which the choke valve is held tightly closed during starting operations when the engine is hot, it serves to prevent overchoking under these conditions, and, by preventing the choke valve from becoming or remaining tightly closed at any time when the engine is hot, it reduces the likelihood of the engine being stalled as a result of flooding. 50

The mechanism shown in Figure 8 differs from 55 that shown in Figures 1 to 5 only in that there is included therein a bimetallic thermo-sensitive strip 90 one of whose ends is secured by a screw 91 to the body 18 adjacent the free end of the arm 32 of the keeper 29. The strip 90 is, of 60 course, affected by the heat radiated from the engine on which the mechanism is installed and is so constructed and arranged that when its temperature is below a predetermined value its free end stays out of the path of movement of 65 the arm 32 of the keeper 29 and when its temperature exceeds this predetermined value its free end moves into the path of the arm 32 and prevents it moving into the effective field of attraction of the magnet 33. It will be apparent that, 70 while in general, the strip 90 and the parts associated with it have the same function and operate in the same manner as the thermo-sensitive element 84, the former cannot unseat the arm 32 of the keeper 29 from the magnet 33 or serve as 75

a variable limit to the approach of the arm 32 to the magnet 33 but functions either not at all or to prevent the arm 32 approaching within a fixed distance of the magnet 33 when the temperature 5 of the engine exceeds a definite predetermined value.

In Figure 9 of the drawings, the reference character 92 indicates the intake manifold of an 10 internal combustion engine. Although it is not shown, it is to be assumed that there is connected to the intake manifold 92 a carburetor similar to that shown in Figure 1 and that the rod 93 shown 15 in Figure 9 is connected to the choke valve of this carburetor in the manner that the rod 24 is connected to the choke valve of the carburetor shown in Figure 1.

In the upper wall of the intake manifold 92, there is provided an opening 94 which is closed by 20 a plate 95. The plate 95 is secured to the manifold by screws 96 and constitutes the body of the embodiment of my invention which is illustrated 25 in Figure 9.

On the under surface of the plate 95 there are 30 formed two bosses 97 and 98 which project into the intake manifold 92 and are spaced longitudinally thereof. In a slot 99 in the boss 97, there is seated one end of a bimetallic thermo-sensitive strip 100. The other end of the strip 100 extends into a bore 101 in the boss 98 and abuts against a set screw 102 which is threaded into the bore.

Through the plate 95 midway between the bosses 97 and 98 extends an opening 103, which is sealed by a flexible diaphragm 104. Screws 105 clamp the edges of the diaphragm 104 between the plate 95 and an annular member 106 which surrounds the opening 103. On the upper surface of the annular member 106, there are formed ears 107 to which one end of a lever 108 is pivotally connected by a pin 109. The other 40 end of the lever 108 is pivotally connected to the rod 93 by a pin 110. Through the center of the diaphragm 104 extends a rod 111 whose lower end is suitably secured to the strip 100 and whose upper is pivotally connected to the lever 108 by a pin 112. The hole in the diaphragm 104 through 45 which the rod 111 extends is sealed and the rod is secured to the diaphragm by discs 113 between which the central portion of the diaphragm is clamped.

The general operation of the mechanism shown 50 in Figure 9 will be apparent from what has been said with respect to the operation of the mechanisms illustrated in the previous figures. When the pressure in the intake manifold 92 falls or the 55 temperature rises, the diaphragm 104 and the thermo-sensitive strip 100 tend to flex downwardly and open the choke valve which is connected to the rod 93, and when the pressure in the intake manifold rises or the temperature falls 60 the diaphragm and the thermo-sensitive element tend to flex upwardly and close the choke valve. However, it is to be noted that the thermo-sensitive strip 100 differs from the thermo-sensitive element 26 in two important respects, viz., (1) 65 that it is located within the intake manifold instead of in juxtaposition to the exhaust manifold and is, therefore, affected by the temperature of the combustible mixture travelling from the carburetor to the cylinders of the engine rather than by the temperature of the exhaust manifold and 70 (2) that it is a "two position" or "snap" type device, that is to say a device which moves instantaneously from one to the other of the two positions in which it is shown in the drawing and does 75 not occupy any intermediate position except in-

stantaneously. What is said in the last clause of the next preceding sentence is, of course, subject to the qualification that while in either of the two positions illustrated in the drawings the thermo-sensitive strip 100 is capable of functioning within limits as a spring without shifting to the other position. 5

It will, of course, be understood that, if desired, a balanced instead of an unbalanced choke valve 10 may be employed in conjunction with the mechanisms herein disclosed.

Although I have shown and described preferred 15 embodiments of my invention, it is to be understood that this has been done by way of example and not by way of limitation and that the scope 20 of my invention is to be determined only by the appended claims.

I claim:

1. In an internal combustion engine, a carburetor in which there is incorporated a choke valve, means for resisting the initial movement of the choke valve from its closed toward its open 25 position, and a member responsive to engine operating conditions and a thermally actuated member of which both are capable of adjusting the choke valve so connected to the first specified means that they may apply thereto a force which tends to overcome the resistance offered by it to the initial movement of the choke valve from its closed toward its open position and thereafter regulate the position of the choke valve. 30

2. In an internal combustion engine, a carburetor in which there is incorporated a choke valve which is so unbalanced that flow of air into the carburetor tends to open it, a member in which there is provided a passage which connects the carburetor with a cylinder of the engine, means for resisting the initial movement of the choke valve from its closed toward its open position, and means for adjusting the choke valve which includes a member responsive to pressure conditions within the mentioned passage and a thermally actuated member of which each is so connected to the first specified means that it may apply 45 thereto a force which tends to overcome the resistance offered by it to the initial movement of the choke valve from its closed toward its open position. 50

3. In an internal combustion engine, a carburetor in which there is incorporated a choke valve, a member responsive to engine operating conditions and a thermally actuated member of which both are capable of adjusting the choke valve, 55 means for resisting the initial movement of the choke valve from its closed toward its open position, and means for varying the resistive effect of the last specified means in accordance with changes in temperature.

4. In an internal combustion engine, a carburetor in which there is incorporated a choke valve which is so unbalanced that flow of air into the carburetor tends to open it, a member in which there is provided a passage which connects the carburetor with a cylinder of the engine, means for adjusting the choke valve which includes a member responsive to pressure conditions within the mentioned passage and a thermally actuated member, means for resisting the initial movement of the choke valve from its closed toward its open 65 position, and means for varying the resistive effect of the last specified means in accordance with changes in temperature. 70

5. In choke valve operating mechanism, a body in which there is provided a recess, a shaft 75

which extends through the recess and is journalled in the walls of the body, and a magnet and an armature located within the recess in the body and secured one to the shaft and the other 5 to the body.

6. In an internal combustion engine, a carburetor in which there is incorporated a choke valve and operating mechanism for the choke valve in which there is included a body in which there is 10 provided a recess, a shaft which extends through the recess and is journalled in walls of the body, pressure and thermally actuated elements carried by the body and connected to the shaft, and means for releasably holding the shaft against 15 rotation located within the recess.

7. In an internal combustion engine, a carburetor in which there is incorporated a choke valve and operating mechanism for the choke valve in which there is included a body in which there is 20 provided a recess, a shaft which extends through the recess and is journalled in walls of the body, a thermally actuated element connected to the shaft and to the body, a pressure actuated element located within a recess in the body and 25 connected to the shaft, and means for releasably holding the shaft against rotation located within the recess.

8. In carburetor choke valve latching mechanism, a magnet and an armature of which one is 30 movable toward and away from the other, and a thermally actuated element which is carried by one of the magnet and armature and limits the approach of one toward the other.

9. Means for releasably holding the choke valve 35 of a carburetor which includes a magnet, an armature which is movable toward and away from the magnet, and a thermally actuated element which is carried by the armature and limits the approach thereof toward the magnet.

- 40 10. Means for releasably holding the choke valve of a carburetor which includes a magnet and an armature of which one is movable toward and away from the other, and a thermally actuated element which is fixedly mounted with respect to one of the magnet and the armature and 45 limits the approach of one toward the other.

11. In carburetor choke valve latching mechanism, a magnet, an armature which is movable toward and away from the magnet, and a thermally actuated element which is fixedly mounted with respect to the magnet and arrests the approach of the armature toward it.

12. In an internal combustion engine, a carburetor in which there is incorporated a choke valve, 55 a member in which there is a passage which connects the carburetor with a cylinder of the engine, a member responsive to pressure variations within the mentioned passage connected to the choke valve so that it tends to move the choke valve toward its 60 open position when the pressure within the mentioned passage falls, and means, including a magnet and an armature, which opposes movement of the choke valve toward its open position by the last specified member and 65 is effective while the engine is operating under its own power.

13. In an internal combustion engine, a carburetor in which there is incorporated a choke valve which is so arranged that the flow of air into 70 the carburetor tends to open it, a member in which there is a passage which connects the carburetor with a cylinder of the engine, a member responsive to pressure variations within the mentioned passage connected to the choke valve so 75 that it tends to move the choke valve toward its

open position when the pressure within the mentioned passage falls, and means, including a magnet and an armature, which opposes movement of the choke valve toward its open position by the last specified member and is effective while the engine is operating under its own power.

14. In an internal combustion engine, a carburetor in which there is incorporated a choke valve, a member in which there is a passage which connects the carburetor with a cylinder of the engine, a thermally actuated element associated with the choke valve, means, including a magnet and an armature, which tends to hold the choke valve closed and is effective while the engine is operating under its own power, and a member 10 responsive to pressure variations within the mentioned passage connected to the choke valve so that it tends to move the choke valve toward its open position when the pressure within the mentioned passage falls, and, thereafter, in conjunction with the thermally actuated element to regulate 15 the position of the choke valve.

15. In an internal combustion engine, a carburetor in which there is incorporated a choke valve which is so arranged that the flow of air into the carburetor tends to open it, a member in which there is a passage which connects the carburetor with a cylinder of the engine, a thermally actuated element associated with the choke valve, means, including a magnet and an armature, 20 which tends to hold the choke valve closed and is effective while the engine is operating under its own power, and a member responsive to pressure variations within the mentioned passage connected to the choke valve so that it, in conjunction with the flow of air into the carburetor, tends to move the choke valve toward its open 25 position when the pressure within the mentioned passage falls and, thereafter, in conjunction with the thermally actuated element, to regulate the 30 position of the choke valve.

16. In an internal combustion engine, a carburetor in which there is incorporated a choke valve, means for resisting the initial movement of the choke valve from its closed toward its open position, a thermally actuated member and a member 40 responsive to changes in speed of the engine connected to the choke valve and the first-specified means so that they may apply to the latter a force which tends to overcome it and, thereafter, 45 regulate the position of the choke valve.

17. In an internal combustion engine, a carburetor in which there is incorporated a choke valve, a member responsive to changes in speed of the engine connected to the choke valve so that it 55 may move the choke valve toward its open position, and means, including a magnet and an armature, which opposes movement of the choke valve toward its open position by the specified member and is effective while the engine is operating under its own power.

18. In an internal combustion engine, a carburetor, a valve for regulating the ratio of fuel to air in the combustible mixture supplied to the engine by the carburetor, a housing which consists 65 of a body and a cover, a bellows disposed within the housing with its open end clamped between the cover and the body and its closed end operatively connected to the valve, and means through which fluid may be admitted to and withdrawn 70 from the interior of the bellows through the cover to extend and contract the bellows.

19. In an internal combustion engine, a carburetor, a valve for regulating the ratio of fuel to air in the combustible mixture supplied to the 75

5 engine by the carburetor, a housing which consists of a body and a cover, a shaft journaled in the body and operatively connected to the valve, a bellows disposed within the housing with its open end clamped between the cover and the body and its closed end operatively connected to

the shaft, and means through which fluid may be admitted to and withdrawn from the interior of the bellows through the body and the cover to extend and contract the bellows.

LESTER E. PERRINE.
